Fig. 2

FIG. 1 is a left front perspective view of a scuff preventing heel cover showing my new design;

FIG. 2 is a left front perspective view thereof in open condition;

FIG. 3 is a left side elevational view thereof the right side being a mirror image thereto;

FIG. 4 is a front elevational view thereof;

FIG. 5 is a rear elevational view thereof; and

FIG. 6 is a top plan view thereof.

I claim:

The ornamental design for a scuff preventing heel cover, substantially as shown and described.
